UNITED STATES PATENT OFFICE.

HIRAM HOLDEN, OF MANCHESTER, NEW HAMPSHIRE.

MARGINAL STRIP FOR BOOTS AND SHOES.

1,250,459.

Specification of Letters Patent. Patented Dec. 18, 1917.

Application filed April 5, 1917. Serial No. 160,031.

To all whom it may concern:

Be it known that I, HIRAM HOLDEN, a citizen of the United States, and resident of Manchester, N. H., have invented certain new and useful Improvements in Marginal Strips for Boots and Shoes, of which the following is a specification.

My present invention relates to the manufacture of boots and shoes and particularly to a form of border strip, being an adaptation of the invention made the subject of Letters Patent granted August 8th, 1916, No. 1,193,687, and No. 1,193,688, for use in connection with the production of what is known as McKay and welt shoes. In the making of these shoes with box toes steam is used to temper the box so it can be made to conform readily to the shape of the last, and the sized cloth strip alone referred to in my earlier patents would not give the results desired to be obtained, as the steaming process would wilt it. I have aimed to adapt my invention for use in connection with these types of shoes and also for use with what is known as brogans or extra heavy men's shoes, the change consisting in utilizing with the paper strip of my former patents a backing of plain or sized cloth which is secured to the strip by gum or other medium, and my invention contemplates the use with this backing of a strip on one or both sides of the cloth. The completed strip can be either lapped or butted to the portion it is attached to.

In the accompanying drawing I have shown the cloth alone, deeming it unnecessary to show it in connection with the upper of a shoe, as in all other respects, except that indicated, the method of use is exactly as heretofore described.

In the drawing:

Figure 1 shows the strip in elevation.

Fig. 2 a section of the same, and

Fig. 3 is a modification in section showing two paper strips with the sized cloth between.

In these figures my corrugated strip of thin stiff material, preferably paper, is shown at A and secured to it is a strip of sized cloth B. The two strips may be secured together by gum in any suitable manner, whether by applying the gum to the paper and pressing the paper and cloth together, or applying the adhesive to the cloth and pressing the paper thereupon. As shown in Fig. 3 I may use a modification consisting of two paper strips with the interposed strip of cloth. This strip may be corrugated at the time the paper and cloth are pressed together or afterward.

As I have stated it is necessary to support the strip against wilting when utilized in a shoe which is subjected to steam in the manufacture and at the same time I have found that sized cloth alone cannot be used with good results in the manufacture of this type of shoes, for the reason that the steam would instantly remove the sizing but by using the outer covering of paper and the inner supporting strip of sized cloth I prevent the wilting of the strip by the supporting medium of the cloth and I protect the sized cloth from the action of the steam by the outer layer or layers of paper.

The method of attaching is as heretofore described, except that in the manufacture of shoes of the McKay type the strip would not be cut away, as stated in my earlier Patent No. 1,193,687.

What I claim is:

As an article of manufacture a marginal strip for use in the manufacture of boots and shoes comprising a corrugated narrow composite strip of paper and a backing of woven material.

In testimony whereof I have affixed my signature,

HIRAM HOLDEN.

Witnesses:

HAROLD W. NUTE,
ANNIE M. TENNANT.
